UNITED STATES PATENT OFFICE.

HENRY LANDON, OF MASSILLON, OHIO.

LAMP-LIGHTING DEVICE.

SPECIFICATION forming part of Letters Patent No. 397,923, dated February 19, 1889.

Application filed September 12, 1888. Serial No. 285,196. (No model.)

To all whom it may concern:

Be it known that I, HENRY LANDON, a citizen of the United States of America, residing at Massillon, in the county of Stark and State 5 of Ohio, have invented certain new and useful Improvements in Lamp-Lighting Devices, of which the following is a specification, reference being had therein to the accompanying drawings.

This invention relates to that class of devices for lighting lamps in which a match is forced between yielding serrated jaws and caused to be lighted; and the objects of my improvement are to provide a lighting device 15 suitable for lighting locomotive head-lights through the top of the chimney of said light, and consisting of parts capable of being easily carried in the pocket of the attendant. I accomplish these objects by the construction 20 illustrated in the accompanying drawings, in which—

Figure 1 is a side view of a lamp-lighting device constructed in accordance with my invention. Fig. 2 is a longitudinal section of 25 the same, showing a match therein. Fig. 3 is a longitudinal section of the same with the match forced out and lighted. Fig. 4 is a longitudinal section of the end of the device from which the hand-plunger projects. Fig. 5 is 30 a longitudinal section of the match-carrying end of the device. Fig. 6 is a perspective view of the match-carrying end, showing the serrated jaws thereof.

In said drawings, A represents a tubular 35 case having four longitudinal splits in one end to produce therefrom a pair of spring-jaws, a, having their edge bent inwardly and serrated. Within this case is placed a plunger, B, having a chamber, b, in one end of proper size to 40 closely retain one end of a match, m. The length of said plunger is of such size relatively to the case A that one end thereof projects sufficiently from said case, as shown in Fig. 5, to be grasped between the thumb and 45 finger to withdraw it from the case for the insertion of a match.

To render the device long enough to reach the wick within large locomotive head-lights, but permit it to be easily carried in the pocket 50 of the engineer or fireman, one end of the case

A is connected to one end of a case, D, that is provided with a socket, d, into which is cut an angular groove, d², to receive a pin, a², projecting radially from the side of the case A, and form therewith a bayonet-joint to unite 55 these parts. The opposite end of the case D is provided with a flat head, D², whereby it may be easily retained, and within said case is placed a plunger, E, either solid or tubular, having a flat head, e, by which it may be advanced into the case D and its inner end made to force forward the plunger B and carry the match m between the jaws a. To prevent the plunger E falling from the case D, it is retained connected therewith by means of a pin, 60 e², projecting from its side through a long slot, a³, formed in the side of said case.

When this device is to be used to light a lamp or locomotive head-light through the top of the chimney, if the parts are united they 70 are first disjointed, as shown in Figs. 4 and 5, the plunger B is withdrawn from its case, and one end of a match is then inserted into the chambered end of said plunger B. The socketed case D is then united to the case A, and the 75 parts assume the position shown in Figs. 1 and 2. The lighting device is then carried by the attendant to the locomotive head-light, who temporarily removes the hood, and, holding the case D under its head D² between his first 80 and second fingers, inserts the device into the chimney and presses with his thumb upon the flat head e of the upper plunger, E. The latter advances the plunger B, and forcing the match between the serrated jaws causes it to be 85 lighted in close proximity of the wick and out of the wind that may be blowing.

I am aware that tubular lamp-lighters have been provided with serrated spring-jaws at one end, and also with an opening in the side 90 for the introduction of a match, with a plunger therein propelled by hand or by means of a spring, and that said spring was retracted by a pin passing through an angular slot in the tube, and I do not claim either of these 95 specific features.

Having now fully described my invention, I claim—

1. In a lamp-lighting device, the combination of the tubular case A, having inwardly- 100

bent and serrated jaws at one end and a radial pin, a^3 , at the other, and a tubular case, D, having a socket and angular groove at one end and a head, D^2 , at the other, with a plunger, E, permanently retained in said case, and a removable plunger, B, within the case A, substantially as and for the purpose described.

2. In a lamp-lighting device, the combination of the tubular case A, having inwardly-bent and serrated jaws at one end, a tubular

case, D, a socketed joint uniting said cases, a plunger, E, permanently retained in the case D, and a removable plunger in the case A, substantially as and for the purpose described.

In testimony whereof I affix my signature in presence of two witnesses.

HENRY LANDON.

Witnesses:

CLEMENT RUSSELL,

ROBERT W. McCaughey
